UNITED STATES PATENT OFFICE.

ARTHUR KEAN, OF MANCHESTER, AND JOHN OAKDEN POTTER, OF CHINLEY,
ENGLAND.

VACUUM APPARATUS FOR STRIPPING CARDING ENGINES.

Application filed October 21, 1927, Serial No. 227,808, and in Great Britain October 26, 1926.

These improvements relate to vacuum apparatus for the stripping of the cylinders of carding engines, of that type wherein a nozzle carrier, bearing exhaust nozzles for the vacuum stripping of the main cylinder and the adjacent doffer cylinder of the carding engine, traverses a double screw shaft and is tilttable to remove the nozzles from the cylinders. Such tilting has hitherto been effected by the displacement of a guide rod, the slackening of screws, or like positive operations. The objects of our improvements are to provide in apparatus of this type means for traversing the nozzle carrier whilst maintaining the same in correct relation to the cylinders being stripped; for tilting the carrier when desired without interfering in any way with the supporting or adjusting means, and for adjusting with exactness the position of the nozzles. The apparatus is thus improved and simplified in its parts.

With these objects in view our improvements comprise a rail on each side of the screwed shaft and parallel therewith, members on the nozzle carrier slidably engaging with these rails. A clamp which is pivoted to be swung out of the way when desired, normally acts as a stop at one end of the screwed shaft when the nozzle carrier is in stripping operation. When it is desired to tilt the nozzle carrier when stripping is suspended the clamp is merely swung over and the nozzle carrier can then be drawn further along so that the slidable member before referred to may leave the side rails or one of them, the tilting thus taking place automatically. The disposition of the parts is therefore such that when the nozzles are again to come into operation for stripping it is only necessary to move the carrier along and cause its sliding members again to make contact with the side rails, swing the pivoted clamp over to the position where it acts as a stop for the nozzle carrier, and stripping can again commence with the apparatus in exact position which it before occupied in relation to the card cylinders.

The improvements in a very convenient form as to mechanical details will now be fully described with reference to the accompanying drawings wherein:—

Figure 1 is an elevation, viewed from the doffer cylinder side of the carding engine, of the improvements;

Figure 2 is a plan of Figure 1; and

Figure 3 is an end view taken from the right of Figure 1, showing the arrangement of the pivoted clamp member and other details.

Referring to the drawings the nozzle carrier 50 is provided with the nozzle 4 which is adapted to strip the main cylinder, and with the nozzle 5 for stripping the doffer cylinder. The doffer cylinder is indicated at A in Figure 3, and the main cylinder for the stripping of which nozzle 4 is provided is not shown. Nozzle member 6 has connected thereto a flexible tube which is in communication with an exhausting means, and a handle for a usual type of nozzle valve is shown at 7. The nozzle carrier is mounted on a central sleeve or boss 8 having a crutch of known type which engages in the thread of a double screwed shaft 9 through a longitudinal slot 10 formed in an outer sleeve 11. The latter surrounds the shaft 9 and not only serves for the smooth traverse of the nozzle carrier along the cylinder surfaces but prevents the filling up of the thread of shaft 9 with dust and fly.

The shaft 9 is rotated by means of a pulley 12 which itself is driven at the desired speed from any convenient part of the carding engine drive, and the said shaft is borne in the end brackets 13 and 14 which are themselves secured to further brackets 15 and 16 secured to the side cheeks 17^a of the carding engine. To the brackets 15 and 16 are bolted two up-standing brackets 17 and 18 to which are secured by bolts 19 two rails 20 and 21 which are parallel to the shaft 9 but at different levels as seen clearly in Figure 3.

On the main cylinder nozzle 4 is cast a lug 22 tapped to receive an adjusting screw 23, and the doffer nozzle 5 is provided similarly with a lug 24 and adjusting screw 25. On the bearing bracket 14—see Figure 3 and also right hand side of Figures 1 and 2—is cast a lug 26 on which is pivotally mounted by the pivot pin 27 a semi-circular clamp 28 which normally, when the apparatus is in use is turned up to embrace and rest upon the upper surface of the sleeve 11. This clamp, in this position, serves therefore as a removable stop for the nozzle carrier at the end of its traverse.

When the stripping apparatus is in operation the nozzle carrier, engaged with the dou-

- ble screw shaft 9 through the slot 10, of sleeve 11 as stated, performs the reciprocating traverse of the shaft 9 in known manner, the clamp 28 being turned over upon the sleeve 11 to act as a stop but the nozzle carrier has at all points in its traverse a three point support, to wit, the sleeve 11, the rail 20, and the rail 21, the ends of the screws 23 and 25 acting as shoes which slide along the said rails. 10 A touch ensures that the nozzle carrier at the end of its traverse will engage the return screw of shaft 11. When it is desired to withdraw the nozzle carrier from its cylinder stripping position the clamp 28 is swung over 15 to the position shown in dotted lines in Figure 3 and the said nozzle carrier is then free to be drawn further along the sleeve 11, until the screws 23 and 25 leave the ends of rails 20 and 21. The side supports thus being removed the nozzle carrier can be swung around the sleeve 11 as a centre and it is then out of action until again required.

The rails 20 and 21 are described and shown as being of the same length, but one of them 25 may be shorter than the other so that when the clamp 28 is in the position of Figure 3 that screw 23 which acts as a shoe on the said shorter rail will fall as a result of the movement of the nozzle carrier. 30 Again, should it be thought at any time sufficient to dispense with the sleeve 11, the nozzle carrier may ride upon the screwed shaft 9 and the clamp be adapted to embrace a reduced neck on the end of the shaft, the 35 function being exactly the same as above described. We prefer the protective sleeve 11 for the reasons already stated.

The provision of adjustable screws 23 and 25 allows of a micrometric adjustment of the 40 nozzle carrier in a very simple and convenient manner and the mounting of brackets 13 and 14 in their cradle brackets 15 and 16 ensures that when it is thought desirable or expedient to remove the shaft 9 and rails 20 and 21, these 45 members will, when again placed in position,

resume the exact position they occupied before removal.

We claim:—

1. In a vacuum stripping apparatus for carding engines consisting of a double 50 screwed shaft on which an exhaust nozzle carrier is mounted for reciprocating traverse along the said shaft, a rail on either side of the shaft and parallel therewith, a member on the said nozzle carrier slidably engaging with each such rail a clamp which normally acts as a stop for the nozzle carrier in its stripping traverse, the said clamp being pivoted to be swung out of the way when desired to allow of the nozzle carrier sliding members being 60 drawn out of contact with one or both of the side rails, for the purpose set forth.

2. In vacuum stripping apparatus for carding engines of the type referred to and having the features claimed in claim 1, members 65 on the nozzle carrier which members slidably engage with side rails the said members being screws which are vertically adjustable.

3. In vacuum stripping apparatus for carding engines of the type referred to and 70 having the features claimed in claim 1, a protective sleeve for the double screwed shaft on which sleeve the nozzle carrier may move, and a longitudinal slot in the said sleeve to allow engagement of the nozzle carrier with the 75 threads of the double screw shaft which the sleeve encloses.

4. Vacuum stripping apparatus for carding engines of the type referred to and having the features claimed in claim 1, and further characterized in that the double screw shaft and side rails are secured in end brackets which themselves are removably screwed in cradle brackets substantially as hereinbefore set forth. 80

85 In testimony whereof we have hereunto set our hands.

ARTHUR KEAN.
JOHN OAKDEN POTTER.
